UNITED STATES PATENT OFFICE.

JOHN F. BEBB, OF NEVADA, IOWA.

EXTENSION-SHELF FOR WRITING-TABLES.

974,340.

Specification of Letters Patent.

Patented Nov. 1, 1910.

Application filed October 18, 1909. Serial No. 523,128.

To all whom it may concern:

Be it known that I, JOHN F. BEBB, a citizen of the United States, residing at Nevada, in the county of Story and State of Iowa, have invented a certain new and useful Extension-Shelf for Writing-Tables, of which the following is a specification.

My invention is especially adapted for use in connection with writing tables of the kind used in hotels and public places such as are ordinarily used by the traveling public who must frequently have ready access to suit cases, grips and the like when using the writing desk.

15 The object of my invention is to provide an extension shelf of simple, durable and inexpensive construction that, when in its folded position, will not project beyond the side of the table nor will it restrict the space 20 under the table for the users' legs, and also to provide an extension shelf that may be readily and easily moved to extended position, and when in said position will support a suit case or grip in position where the 25 contents thereof will be readily accessible to a person seated at the desk, and also to provide a shelf of this kind that will be normally retained in its folded position without the use of latches or fastening devices.

30 My invention consists in certain details, in the construction, arrangement and combination of the various parts of the device, whereby the objects contemplated are attained, as hereinafter more fully set forth, 35 pointed out in my claims, and illustrated in the accompanying drawings, in which—

Figure 1 shows a perspective view of a desk having two of my improved extension shelves applied thereto, one being in folded 40 position and the other being in an extended position, and Fig. 2 shows a vertical, central, longitudinal, sectional view of a table provided with two of my improved shelves, one being shown extended and the other folded.

45 Referring to the accompanying drawings, I have used the reference numeral 10 to indicate a table top of the kind ordinarily used in writing tables and provided with a transverse upright partition 11 at its central portion to divide the table into two parts for 50 use by two persons seated at opposite ends of the table. At the corners of the table are the supporting legs 12, and at the central portion of the table at the sides thereof are 55 the downwardly extending shelf supporting members 13 fixed to the table top. At the

sides of the table below the top are the longitudinal strips 14 which are set in slightly from the adjacent edge of the table top.

Each of the extension shelves comprises 60 two main side pieces 15 connected by means of the cross slats 16. These side pieces 15 are pivotally connected to one of the adjacent legs 12 and the support 13 by means of a rod 17. At the free ends of the side pieces 15 are the extensions 18 which are of approximately half the thickness of the side pieces proper. The parts are so arranged in proportion that when the side pieces 15 are in their folded positions, the said extensions 70 18 will engage and rest against the adjacent strip 14 and the said upper ends of the side pieces 15 will incline inwardly a slight distance toward the longitudinal center of the table to thereby hold the shelf in its folded 75 position by gravity.

Attached to the free ends of the side pieces 15 is a rod 19 having a handle 20 whereby it may be readily and easily grasped by an operator for the purpose of moving the side 80 pieces 15 to their extended positions. The said side pieces 15 also extend a considerable distance below the pivoting rod 17, and I have provided means whereby the side pieces 15 will be rigidly held in a horizontal position as follows: Secured to the leg 12 and the support 13 are two blocks 21 in position to be engaged by the lower ends of the side pieces 15 when said side pieces are in a horizontal position to thereby limit the downward- 90 movement of the outer ends of said side pieces.

It is desirable that the extension shelf, when in position for use, will be only a comparatively short distance below the table 95 top, hence in order to provide a shelf of sufficient width, it is necessary that this shelf of itself be capable of folding so that it may be contained, when folded in the space between its pivotal point, on the top of the 100 table. For this purpose I have provided two extension side pieces 22, each having its inner end at 23 shaped to fit against the extension 18 and hinges 24 which are provided to connect the parts 23 with the side pieces 105 15. By this arrangement it is obvious that the side pieces 22 will be supported not only by the hinges 24 but by the extensions 18 so that when in a horizontal position the side pieces 22 will be firmly held against downward movement at their outer ends. These 110 side pieces are connected by means of the

cross slats 25 which are uniform in size and shape with the cross slats 16. The said side pieces are of such a length that the operator may first grasp the cross pieces 25 and fold 5 the side pieces 22 back over the slats 16 and then the side pieces 15 may be folded upwardly so that the extensions 18 thereof will engage the strip 14.

In practical operation, it is obvious that 10 my improvement may be readily, quickly and easily applied to an ordinary writing table by simply securing to it the rods 17 and the stop blocks 21. When the extension shelf is in its folded position, it is obvious 15 that it does not project beyond the side of the table nor does it extend inwardly beyond the legs of the table so that when in its folded position it will not interfere or be in the road of the legs of the person using the 20 table. By having the shelf made of two parts, one of which folds over the other, the pivotal point of the shelf may be quite close to the top of the table so that the articles placed thereon will be readily accessible to 25 the person seated at the table. Obviously the device may be extended for use by simply grasping the handle 20 and pulling it outwardly, and then unfolding the outer portion of the shelf to the position shown at 30 the left in Fig. 1, and the shelf may be folded up by first doubling the outer part of it over the inner part and then swinging the inner part upwardly to position past a dead center where the extensions 18 will engage 35 the side strip 14 of the table; hence, no latches or other fastening devices are necessary for supporting the extension shelf in either position, and no part of the shelf extends downwardly toward the floor where it 40 might interfere with sweeping the floor.

I claim as my invention—

1. A device of the class described, comprising a table, an extension shelf comprising two arms pivotally supported below the 45 table top and capable of swinging upwardly to a vertical position below the table top, said arms each having an extension at the

lower side of its outer end, cross slats fixed to said arms, two auxiliary arms hinged to the outer ends of the aforesaid arms, hinges 50 for connecting the auxiliary arms with the first mentioned arms, said extensions on the first mentioned arms being arranged to support the auxiliary arms in a horizontal position in line with the first mentioned arms, 55 cross slats on the auxiliary arms, said auxiliary arms being capable also of folding to position overlapping the first mentioned arms and of folding under the table top, and means for limiting the downward movement 60 of the first mentioned arms when in their extended positions, for the purposes stated.

2. A device of the class described, comprising a table having a strip extending longitudinally thereof at one side below the 65 table top and spaced apart from the edge of the table top, a supporting piece fixed to the table top and extended downwardly at a point midway between the ends of the legs, two extension shelves, each comprising two 70 arms, one pivoted to one of the legs of the table and the other pivoted to said support, stop blocks secured to said leg in said support to be engaged by said arm to hold them in horizontal position, the outer ends of said 75 arms being provided with projecting portions so arranged as to engage the side strip of the table top when the said arms are swung upwardly past a dead center, two auxiliary arms having extensions at the inner ends of the aforesaid arms, hinges arranged at the ends of said extensions on the auxiliary arms and connected to the first mentioned arms, cross slats connecting said auxiliary arms, and a rod connected to the 80 first mentioned arms, and provided with a handle, substantially as, and for the purposes stated.

Des Moines, Iowa, Oct. 9, 1909.
